CLAIM

The ornamental design for an elongate slanted rod toy brick as shown and described.

DESCRIPTION

FIG. 1 is a top perspective view of an elongate slanted rod toy brick.

FIG. 2 is a bottom perspective view of the elongate slanted rod toy brick.

FIG. 3 is a second, top perspective view of the elongate slanted rod toy brick.

FIG. 4 is a second, bottom perspective view of the elongate slanted rod toy brick.

FIG. 5 is a side plan view of the elongate slanted rod toy brick.

FIG. 6 is a second, side plan view of the elongate slanted rod toy brick.

FIG. 7 is a back plan view of the elongate slanted rod toy brick.

FIG. 8 is a front plan view of the elongate slanted rod toy brick.

FIG. 9 is a top plan view of the elongate slanted rod toy brick; and,

FIG. 10 is a bottom plan view of the elongate slanted rod toy brick.

The broken lines in the figures show features of the elongate slanted rod toy brick that form no part of the claimed design.

1 Claim, 10 Drawing Sheets
